UNITED STATES PATENT OFFICE.

FRANK HOFFMAN, OF NEW YORK, N. Y.

STAND FOR FLEXIBLE POSTERS.

Application filed January 25, 1928. Serial No. 249,226.

The objects of this invention are to provide a simple and inexpensive stand for flexible posters which can be quickly set up or taken down and which is suited to being 5 rolled up and shipped with the poster.

Practical embodiments of the invention are illustrated in the accompanying drawing, wherein:

Figure 1 is a broken and part sectional 10 side elevation showing one form of the stand in use supporting a flexible poster.

Figure 2 is a side view of a different form 15 of the support.

Figure 3 is a plan view showing the stand 20 detached.

Figure 4 is a rear perspective view illustrating another form of the stand.

In the past it has been more or less customary to use thrust pieces and stretching 25 members for holding the poster stretched taut and to provide a rearwardly extending prop or props for supporting the stretched poster in upright relation.

In the present invention, thrust pieces, 30 stretching members and props are all eliminated by the provision of a single stand having only two legs joined in angularly related fashion and connected with opposite edges of the poster.

35 In the simplest form of the invention illustrated, that is, in Figure 4, the two legs of the stand, designated 5 and 6 respectively, are joined at an acute angle by having the first set in a socket 7 in the second and 40 the ends of these two members are engaged in sockets 8, 9 in the under side of the top edge strip 10 and in the back of the lower edge strip 11 of the poster 12.

The parts 5 and 6 are shown as rods or 45 dowels, the lower rod 6 resting on the floor or support on which the lower edge strip of the poster rests and the upper rod 5 inclining forwardly and serving as a support for the upper edge strip and the poster dependent therefrom. With this stand it is 50 only necessary to insert the base rod 6 in the back of the lower poster strip, then engage the lower end of the upright rod 5 in the socket at the rear end of the base rod 55 and the upper end of the upright in the socket in the under side of the upper edge strip. The poster is just as easily taken down by simply pulling the upper edge strip off the upper end of the upright, pulling the upright out of its socket in the base rod and then pulling the base rod out of its

socket in the lower edge strip, whereupon the two pieces 5 and 6 may be rolled with the poster.

The two parts of the stand may be permanently and resiliently connected as by means of a coiled spring shown at 13 in Figure 1 engaged over the shouldered ends 14 of the rods or by a flat spring strip as shown at 15 in Figure 2 hingedly connected 65 in slots 16 in the end portions of the rods by rivets or similar fastenings 17. This pivoting action of the spring connecting strip is desirable because it permits the rods to be brought together in side by side relation, as shown in Figure 3, for shipping purposes.

The spring force connecting the two rods as in Figures 1 and 2, is sufficient to sustain the rod 5 in raised relation supporting 75 the weight of the poster so that it hangs straight, as indicated. When the poster is of considerable height, the rod 5 may be made in two sections having a telescopic connection, as indicated at 18, enabling the 80 rod to be drawn out to the proper length when it is in use and to be shortened when it is to be packed and rolled with the poster.

What is claimed is:

1. In combination with a flexible poster 85 having an upper edge strip with a socket in the rearward under side of the same and a lower edge strip with a socket in the rearward side of the same, a base prop engaged in the rearward socket in the lower edge 90 strip and extending rearwardly therefrom to rest on the floor as a prop, a rod supported by the rearward end of said base prop, said rod being inclined forwardly over the base prop and engaged at its upper end in 95 the socket in the under side of the upper edge strip and a spring connecting the lower end of the rod with the rearward end of the base prop.

2. As an article of manufacture, a supporting structure for flexible posters comprising supporting members having a combined length greater than the poster length engageable at opposite ends with the opposite edge portions of a flexible poster and a 105 coiled spring connecting the other ends of said members and bendable to permit said opposite ends of the members to be approached sufficiently for engagement with the edge portions of the poster whereby said 110 members may be confined by the poster in angular relation and projecting angularly

- from the back of such a poster both to hold the poster in stretched relation and to engage a supporting surface at the back of the poster to support the stretched poster on such surface.
5. The combination with a flexible poster provided with edge strips having sockets faced to the rear of the poster, of two rod-like members for supporting said flexible poster in extended relation, one of said rod-like members being rigidly engaged with the socket in one of the edge strips and extending rigidly to the rear of the poster, the other rod-like member being rigidly engaged 10 with the socket in the other edge strip and extending rigidly to the rear of the poster, the rearward ends of said two rod-like members standing in closely approached relation at the back of the poster and a spring 15 connecting the approached ends of said rigidly outstanding rod-like members in angled relation, said spring being biased in a straightening direction and thereby exerting force to separate the ends of the rod-like 20 members which are connected with the edge strips whereby to hold the edge strips apart with the flexible body of the poster spread therebetween.
6. In combination with a flexible poster having edge strips, rods each having one end engaged with one of said edge strips and a tubular open-ended spring connector engaged over the opposite ends of said rods, said connector being bendable to resiliently join the rods with their adjoining ends in acutely angled relation and their separated 25 ends holding the edge strips spread apart with the poster material stretched therebetween.
7. The combination with a flexible poster, of two relatively rigid rod-like members for supporting said flexible poster in extended relation, one end of one of said rod-like members being engaged with one edge portion of the flexible poster and one end of the other rod-like member being engaged with the opposite edge portion of the poster and a spring connecting the remaining ends of said rod-like members in angled relation projecting angularly from the poster and exerting a force to separate those ends of the rod-like members which are connected with the edge portions of the poster, to thereby hold the poster stretched taut under the tension of said spring.
- In testimony whereof I affix my signature.
FRANK HOFFMAN.
